UNITED STATES PATENT OFFICE

PAUL BETZLER, OF JACKSON HEIGHTS, NEW YORK

BUILDING SLAB

Application filed November 6, 1930. Serial No. 493,748.

This invention relates to building materials, and more particularly refers to improvements in building units of the interlocking type made in molded form out of originally 5 plastic materials.

The primary object of this invention is to provide a building unit of a novel and improved design comprising a relatively thin web body and two ribs or flanges inwardly 10 extending therefrom, said body and flanges being adapted to interlock with the bodies and flanges of adjoining units so as to form therewith a structure comprising a relatively thin web body and a plurality of beams 15 or column members as the case may be.

Another object is to provide a building unit or slab of the character specified, made of preferably reinforced cementitious material, said unit being cast with two ribs both 20 of which extend for the entire depth of the beam or column to be formed thereby, thus permitting the insertion of more than one series of binding portions connecting adjoining units together.

25 A further object is to provide a building unit or slab of the character specified, readily lending itself to be used as a foundation onto which lathing, or building boards or other similar materials may be easily secured.

30 A still further object is to provide a construction composed of a plurality of elements or units preferably formed of reinforced concrete or other cementitious material, said units being interlocking with one another and 35 being held together to form a complete structure by means of suitable reinforcing and binding elements cooperating therewith.

Other objects and advantages of the present invention will more fully appear as the 40 description proceeds and will be set forth and claimed in the appended claims.

My invention is illustrated in the accompanying drawings, in which:

Fig. 1, is a view in perspective of a building unit or slab embodying my invention;

Fig. 2 is a fragmentary view in perspective partly sectioned of a corner of a building in which building slabs of the type shown in Fig. 1 are employed for the construction 50 of its walls;

Fig. 3 is a plan sectional view thereof;

Fig. 4 is a fragmentary cross sectional view of one of the walls of said building;

Fig. 5 is a partial view in perspective of a floor formed of a plurality of building units 55 of the same type;

Fig. 6 is a fragmentary vertical section showing the manner of building walls of adjoining stories; and Fig. 7 is a cross section in an enlarged scale of the corner unit shown 60 in Figs. 2 and 3;

In a patent entitled, Interlocking unit constructions, issued to me May 6, 1930, #1,757,-763, I have described a building unit or slab of a special construction making it possible 65 to reduce the cost of labor in the construction of buildings as well as the weight of the various structures without impairing their stability or strength.

The building slab or unit described and 70 claimed in said patent, comprises a web body having one of its longitudinal edges inwardly bent at an angle to the surface of said body to form a rib integral therewith and having its other longitudinal edge bent inwardly, laterally and upwardly to form a hook sectioned beam or column member, 75 adapted to receive and to interlock with the rib member of an adjoining unit.

Although I have found said building slab 80 or unit to be entirely satisfactory in use, I have also found in practice that the same requires a rather objectionable amount of care in handling, which is necessary in order to prevent excessive breakages. My expe-

rience has also been in this respect that breakages are likely to occur when the slabs are extracted from the mould, these breakages being mainly due to the difficulties engendered by the hook shaped section of the beam member. The resulting structure is likely to be somewhat weak, because the entire hook sectioned beam overhangs from the web body to which it is attached along a single line of attachment, said beam being hollow and having two bends besides the bend along the line of attachment to the web body.

I have therefore sought to improve the design of the building slab or unit by making a 100 more solid and rigid structure, while retain-

ing all the advantages possessed by the slab or unit forming the subject of my previous patent.

The building slab or unit to which this invention more particularly refers comprises a web body and two ribs which are preferably tapering in section, extending therefrom in proximity of each longitudinal edge thereof, one of said ribs being spaced inwardly of the adjoining longitudinal edge, and the other rib being offset outwardly of the adjoining longitudinal edge so as to form therewith a recess adapted to receive and to interlock with the projecting longitudinal edge of an adjoining slab or unit.

By virtue of its improved design and construction, the resulting slab which is of an extremely light weight makes it possible to build walls or floors of great strength with the expenditure of a comparatively limited amount of labor.

At the same time, the design of the slab is such that the resulting structure is very strong and rigid, easy to mould and adapted to stand a great deal of abuse in handling.

Referring to Fig. 1, it will be observed that my improved slab or unit comprises a web body 10 having a rib 11 extending inwardly therefrom, in proximity of but spaced from one of its longitudinal edges 12, so that the outer surface 13 of said rib defines with said web body a longitudinal tongue 14 along said longitudinal edge 12, extending substantially at right angles to said surface 13.

Said rib is furthermore formed with a longitudinal beaded projection or tenon 15, extending outwardly of surface 13 about midway of its width. The inner surface 16 of rib 11 is preferably made somewhat at a slant so as to cause said rib to have a tapering section wider at the base than at its outer edge. Said slab or unit is also formed with another rib 17, extending along its other longitudinal edge 18, the outer surface 19 of said rib being outwardly spaced from said edge 18, a distance substantially corresponding to the distance of opposite edge 12 from surface 13, forming a longitudinal recess 20 adapted to register and to interlock with the tongue of an adjoining unit, forming a joint therewith.

Said external surface 19 is also formed with a longitudinal channelled recess 21 adapted to register and to interlock with the beaded projection 15 of an adjoining unit forming therewith a tenoned male and female joint.

The inner surface 22 of rib 17 is also preferably made at a slant so as to produce a tapering section wider at the base than along its outer edge. Due to the inclination of surfaces 16, 22, the resulting structure can be easily extracted from the mould after hardening as will be understood and the percentage of breakages occurring during the

moulding process is therefore reduced to a minimum.

By virtue of this construction, one of the outer longitudinal surfaces of one unit may be placed against and interlock with the outer longitudinal surface of an adjoining unit, so that the two adjoining and interlocking ribs will, together, form a beam or column member having a section tapering down towards its outer edge.

A wall can thus be built as shown in Fig. 3 comprising a plurality of interlocking slabs or units 23, 24, etc., the outer surfaces of their web bodies 23', 24', etc., forming a continuous surface which is the outer surface of the wall.

Horizontal binding bars 25, 26, can be inserted as the work progresses alongside the inner surface of the wall and in proximity of the outer edges of the beams thus formed, respectively, through perforations 27, 28, 27', 28', provided through ribs 11, 17 in proximity of one of the ends of the slabs or units.

Another binding bar such as 29 can be similarly inserted at the other end of the slabs or units through perforations 30, 30', also provided through said ribs. Interlocking slabs or units of the type just described can be made of any suitable plastic material or composition which may be selected according to the use for which the slabs or units are intended.

For the construction of outer and main walls, I prefer to make the slab of reinforced concrete as shown in the drawings and in this case, each slab or unit is provided with reinforcing members which may be suitably placed, such as longitudinal bars 31, 32, 33, 34, 35, etc., connected by transversal wire or screen members 36. Openings 27, 28, 30, 27', 28', 30' can be precast in the slabs as will be understood.

When the slabs are placed one against the other along their longitudinal side surfaces, mortar or cement is inserted therebetween, so as to form a strong and positively water proof binding between adjoining units. The slabs are preferably made sufficiently long to extend from floor to floor. The foundation wall 37, shown in Fig. 2 preferably has its upper surface formed with a horizontal groove 38 running all along the wall, the width of said groove substantially corresponding to the distance between the outer surface of the slab and the inner surface of the column members.

After the wall of the first floor has been built and binding bars 29 have been placed in position as shown in Fig. 2, a suitable framework is placed in position so as to cast horizontal beam members running between and also above adjoining column members at the upper end of the slabs. Said horizontal beam members, one of which is shown at 39 in Figs. 2 and 6 are also formed with an upper longitudinal groove 40, within which will be

placed the lower ends of the slabs 41 forming the wall of the next story.

5 A corner formed by two walls constructed in the manner described, is preferably completed by means of a special slab or unit such as shown at 42, in Figs. 2 and 3. The two end slabs or units 43, 44 of the two walls are directed at right angles to each other, and the corner unit 42 is inserted therebetween, so as to interlock therewith.

10 Slabs or units 43, 44 are preferably arranged with their recessed longitudinal surfaces adjoining and interlocking with the corner unit, so that a corner unit of symmetrical construction can be used.

15 The corner slab or unit 42 comprises two web sections 45, 46 at right angles to each other, and two rib sections 47, 48 inwardly projecting respectively from said two web sections, said two rib sections having their outer surfaces directed at right angles to each other, and at right angles to the outer surfaces of their corresponding web sections. Furthermore, the outer surface of each rib 20 section is spaced from the adjoining longitudinal edge 49, 50 of its respective web section, so as to define a longitudinal tongue 51, 52 at the outer side of each web section, said tongue forming with its respective web section a shoulder adapted to nest and to interlock with the longitudinal recess 20 of the adjoining slabs or units.

25 Said outer surfaces of the rib sections are also formed with a beaded projection or tenon 30 53, 54 adapted to register and interlock with the longitudinal groove 21 of the adjoining slab. The inner surfaces 55, 56 of the rib sections are also in this case preferably made at a slant so as to produce a tapering structure for each rib section and so as to form 35 with each other and with the inner surfaces of the web sections a chamber 57, which is preferably filled with concrete as the building progresses as shown in Figs. 2 and 3.

40 45 The resulting structure is therefore a solid corner column which is preferably reinforced all through by vertical reinforcing members 58.

50 When the slabs are made of reinforced concrete or other cementitious material, the edge surfaces of the ribs or rib sections are preferably provided with means such as furring strips 59 adapted to form a foundation onto which lathing, or composition boards or like 55 materials can be easily handled as shown at 60. The slab is preferably built in unit form with the furring strip which may be anchored in the concrete in any suitable manner.

55 60 It is also possible, of course, when pouring the concrete to form the upper wall beam 61 shown in Fig. 4 to insert anchoring boards 62 which will project upwardly therefrom, providing means for securing a wooden strip 62, 63 onto which the roof rafters 64 can be secured in any suitable manner.

The building units or slabs constructed according to my invention can also be used for building floors as shown in Fig. 5 where 65 designates a floor composed of a plurality of interlocking units 66, 67, 68, etc., horizontally 70 arranged, the web portions of said slabs or units forming the floor foundation proper and the interlocking ribs forming the beams.

In the construction of floors, the end slab 66, is preferably made with a flat longitudinal side surface as shown at 69 in Fig. 5, so as to abut directly against the adjoining wall 70 without leaving any unnecessary clearance therebetween.

The beams formed by the rib sections are 80 preferably provided with furring strips 71, onto which lathing or composition boards 72 can be attached. The ribs need not necessarily be directed at 90° to the surface of the web body although it is preferable that their 85 outer surfaces interlock with the outer surfaces of the ribs of adjoining slabs or units, be at right angles to said surface as shown.

The invention may be modified in its various details without departing from the inventive idea; the drawings will therefore be understood as being intended for illustrative purposes only and not in a limiting sense. Accordingly, I reserve the right to carry my 95 invention into practice in all those ways and manners which may enter, fairly, into the scope of the appended claims.

I claim:

1. A building unit of the character specified, comprising a web body having a rib member inwardly projecting therefrom parallel to and in close proximity of each of its longitudinal edges, one of said rib members provided with a longitudinally extending 100 male tenon member projecting from its outer side surface and the other rib member being provided with a longitudinally extending groove adapted to register and interlock with the male tenon member of another similar 105 unit when placed side by side therewith, with its web body in alignment with the web body of said building unit.

2. A building unit of the character specified, comprising a web body having a rib member inwardly projecting therefrom parallel to and in close proximity of each of its longitudinal edges, one of said rib members having its outer side surface directed at right 115 angles to the surface of said web body and spaced inwardly of the adjoining edge thereof to form with said edge a longitudinal side tongue, the other rib member having its outer side surface directed at right angles to the 120 surface of said web body and being offset outwardly of the edge thereof to form with said edge a longitudinal side recess adapted to register and interlock with the tongue of another similar unit when placed side by side 125 130

therewith, with its web body in alignment with the web body of said building unit.

3. A building unit of the character specified, comprising a web body having a rib member inwardly projecting therefrom parallel to and in close proximity of each of its longitudinal edges, one of said rib members having its outer side surface directed at right angles to the surface of said web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess adapted to register and interlock with the tongue of another similar unit when placed side by side therewith with its web body in alignment with the web body of said building unit, the external side surface of one of said rib members being provided with a longitudinally extending male tenon member projecting from its outer side surface, the external side surface of the other side member being provided with a longitudinally extending groove adapted to register and interlock with the male tenon member of another similar unit when placed side by side therewith with its web body in alignment with the web body of said building unit.

4. A building unit of the character specified, comprising a web body having a rib member inwardly projecting therefrom parallel to and in close proximity of each of its longitudinal edges, one of said rib members having its outer side surface directed at right angles to the surface of said web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess adapted to register and interlock with the tongue of another similar unit when placed side by side therewith with the web body in alignment with the web body of said building unit, the inner side surfaces of said rib members being at a slant so as to cause said rib members to have a tapering section wider at the base than at the top.

5. A building unit of the character specified, comprising a web body having a rib member inwardly projecting therefrom parallel to and in close proximity of each of its longitudinal edges, one of said rib members having its outer side surface directed at right angles to the surface of said web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess adapted to register and interlock with the tongue of an-

other similar unit when placed side by side therewith with its web body in alignment with the web body of said building unit, the inner side surfaces of said rib members being at a slant so as to cause said rib members to have a tapering section wider at the base than at the top, said rib members being provided with a longitudinally extending male tenon member projecting from its outer side surface, the external side surface of the other side member being provided with a longitudinally extending groove adapted to register and interlock with the male tenon member of said other unit.

6. A building unit of the character specified, comprising a web body having a rib member inwardly projecting therefrom parallel to and in close proximity of each of its longitudinal edges, one of said rib members being provided with a longitudinally extending male tenon member projecting from its outer side surface and the other rib member being provided with a longitudinally extending groove adapted to register and interlock with the male tenon member of another similar unit when placed side by side therewith with its web body in alignment with the web body of said building unit, said rib members being provided with aligned transversal openings permitting the insertion of binding bars therethrough.

7. A building unit of the character specified, comprising a web body having a rib member inwardly projecting therefrom parallel to and in close proximity of each of its longitudinal edges, one of said rib members having its outer side surface directed at right angles to the surface of said web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess adapted to register and interlock with the tongue of another similar unit when placed side by side therewith with its web body in alignment with the web body of said building unit, the external side surface of one of said rib members being provided with a longitudinally extending male tenon member projecting from its outer side surface, the external side surface of the other side member being provided with a longitudinally extending groove adapted to register and interlock with the male tenon member of said other unit, said rib members being provided with aligned transversal openings permitting the insertion of binding bars therethrough.

8. A building unit of the character specified, comprising a web body having a rib member inwardly projecting therefrom parallel to and in close proximity of each of

- its longitudinal edges, one of said rib members having its outer side surface directed at right angles to the surface of said web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess adapted to register and interlock with the tongue of an adjoining unit with its web body in alignment 70 with the web body of said building unit, the external side surface of one of said rib members being provided with a longitudinally extending male tenon member projecting from its outer side surface, the external side 75 surface of the other side member being provided with a longitudinally extending groove adapted to register and interlock with the male tenon member of an adjoining unit, the inner side surfaces of said rib members being 80 at a slant so as to cause said rib members to have a tapering section wider at the base than at the top, said rib members being provided with a longitudinally 85 extending male tenon member projecting from its outer side surface, the external side surface of the other side member being provided with a longitudinally extending groove adapted to register and interlock with the male tenon member of an adjoining unit, the inner side surfaces of said rib members being 90 at a slant so as to cause said rib members to have a tapering section wider at the base than at the top, and binding bars running through said rib members, along a direction parallel to the outer surface formed by the web bodies 95 of said unit.
11. In a construction of the character described, a corner comprising two units arranged at right angles to each other, each unit including a web body having a rib member inwardly projecting therefrom parallel to and in close proximity of its inner longitudinal edge, the outer side surface of said rib member being directed at right angles to the surface of said web body and being offset 100 outwardly of said edge to form therewith a longitudinal side recess, and a corner locking member comprising a web body portion having a right angled section, and a rib member inwardly projecting therefrom in close proximity of each longitudinal edge thereof, the outer side surface of each rib member being inwardly spaced from the adjoining edge, to form a longitudinal edge tongue registering 105 and interlocking with the longitudinal recess 110 of the adjoining unit.
12. In a construction of the character described, a corner comprising two units arranged at right angles to each other, each unit including a web body having a rib member inwardly projecting therefrom parallel to and in close proximity of its inner longitudinal edge, the outer side surface of said rib member being directed at right angles to the surface of said web body and being offset 115 outwardly of said edge to form therewith a longitudinal side recess, said outer side surface being provided with a longitudinally extending groove, and a corner locking member comprising a web body portion having a right angled section, and a rib member inwardly projecting therefrom in close proximity of each longitudinal edge thereof, the outer side surface of each rib member being inwardly spaced from the ad- 120
10. A construction of the character described, comprising a plurality of units, each unit comprising a web body having a rib member inwardly projecting therefrom parallel to and in close proximity of each of its longitudinal edges, one of said rib members 125 having its outer side surface directed at right

joining edge, to form a longitudinal edge tongue registering and interlocking with the longitudinal recess of the adjoining unit, said outer surface being provided with a longitudinally extending male tenon member registering and interlocking with the longitudinal groove of the outer side surface of the rib member of the adjoining unit.

13. In a construction of the character described, a corner comprising two units arranged at right angles to each other, each unit including a web body having a rib member inwardly projecting therefrom parallel to and in close proximity of its inner longitudinal edge, the outer side surface of said rib member being directed at right angles to the surface of said web body and being offset outwardly of said edge to form therewith a longitudinal side recess, a corner locking member comprising a web body portion having a right angled section, and a rib member inwardly projecting therefrom in close proximity of each longitudinal edge thereof, the outer side surface of each rib member being inwardly spaced from the adjoining edge, to form a longitudinal edge tongue registering and interlocking with the longitudinal recess of the adjoining unit, and binding bars running through the adjoining rib members of said units and corner member.

14. In a construction of the character described, a corner comprising two units arranged at right angles to each other, each unit including a web body having a rib member inwardly projecting therefrom parallel to and in close proximity of its inner longitudinal edge, the outer side surface of said rib member being directed at right angles to the surface of said web body and being offset outwardly of said edge to form therewith a longitudinal side recess, a corner locking member comprising a web body portion having a right angled section, and a rib member inwardly projecting therefrom in close proximity of each longitudinal edge thereof, the outer side surface of each rib member being inwardly spaced from the adjoining edge, to form a longitudinal edge tongue registering and interlocking with the longitudinal recess of the adjoining unit, binding bars running through the adjoining rib members of said units and corner member, and a body of cementitious material filling the chamber formed by the web body portion of said corner locking member and the two rib members inwardly projecting therefrom.

15. In a construction of the character described, two walls at right angles to each other, each wall comprising a plurality of units, each unit including a web body having a rib member inwardly projecting therefrom parallel to and in close proximity of each of its longitudinal edges, one of said rib members having its outer side surface directed at right angles to the surface of said

web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess registering and interlocking with the tongue of an adjoining unit, and corner locking member, comprising a web body portion having a right angled section, and a rib member inwardly projecting therefrom in close proximity of each longitudinal edge thereof, the outer side surface of each rib member being inwardly spaced from the adjoining edge, to form a longitudinal edge tongue registering and interlocking with the longitudinal recess of the adjoining unit.

16. In a construction of the character described, two walls at right angles to each other, each wall comprising a plurality of units, each unit including a web body having a rib member inwardly projecting therefrom parallel to and in close proximity of each of its longitudinal edges, one of said rib members having its outer side surface directed at right angles to the surface of said web body and spaced inwardly of the adjoining edge thereof to form with said edge a longitudinal side tongue, the other rib member having its outer side surface directed at right angles to the surface of said web body and being offset outwardly of the edge thereof to form with said edge a longitudinal side recess registering and interlocking with the tongue of an adjoining unit, a corner locking member, comprising a web body portion having a right angled section, and a rib member inwardly projecting therefrom in close proximity of each longitudinal edge thereof, the outer side surface of each rib member being inwardly spaced from the adjoining edge, to form a longitudinal edge tongue registering and interlocking with the longitudinal recess of the adjoining unit, and binding bars running through the adjoining rib members of said units and corner members.
